CLAIM

The ornamental design for a drill-operated trowel, as shown and described.

DESCRIPTION

FIG. 1 is a top front perspective view of a drill-operated trowel, showing my new design;

FIG. 2 is a front elevation view thereof, the rear elevation view being a mirror image thereof;

FIG. 3 is a top plan view thereof;

FIG. 4 is a right-side elevation view thereof, the left-side elevation view being a mirror image thereof; and,

FIG. 5 is a bottom plan view thereof.

The shade lines in the Figures show contour and not surface ornamentation.
